UNITED STATES PATENT OFFICE.

MOSES S. CLYDE AND WILLIAM WELSH, OF MOUNT OLIVE, ILLINOIS.

BROOM-HEAD.

SPECIFICATION forming part of Letters Patent No. 428,665, dated May 27, 1890.

Application filed September 28, 1889. Serial No. 325,342. (No model.)

To all whom it may concern:

Be it known that we, MOSES S. CLYDE and WILLIAM WELSH, citizens of the United States, residing at Mount Olive, in the county of Ma-
5 coupin and State of Illinois, have invented cer-
tain new and useful Improvements in Broom-
Heads; and we do declare the following to be a
full, clear, and exact description of the inven-
tion, such as will enable others skilled in the art
10 to which it appertains to make and use the
same, reference being had to the accompan-
ying drawings, and to the letters of reference
marked thereon, which form a part of this
specification.

15 The invention relates to the heads which
are employed to connect the handle and straw
of brooms and to clamp the straw firmly at
the upper end.

The invention will first be described in con-
20 nection with the drawings, and then pointed
out in the claims.

Figure 1 of the drawings is an elevation in
perspective of our broom-head attached to the
handle and to the straw; Fig. 2, a detail per-
25 spective of one of the end plates with its
flanges; Fig. 3, a detail view of one of the
side plates; Fig. 4, a detail view of one of the
clamping-wires.

In the drawings, A A represent flat side
30 plates, which have a row of holes a, arranged
at intervals near the bottom edge a', which
may be strengthened by being rolled upon a
wire to form a head.

B B are curved end plates, which are pro-
35 vided with a hole b near each end and with
the parallel flanges b' b', the latter being at
right angles to the plates.

Each of the plates A A and B B has a shoul-
der-cap C, which is nailed or otherwise se-
40 cured to the handle D. These plates may be
formed of any material which combines stiff-

ness and elasticity; but we preferably use
metal for the purpose. After arranging the
plates A A within the flanges b' b' and fast-
ening the caps C to the handle D, we clamp 45
them upon the broom-straw by means of the
wires E, which are passed through the holes
a b and their ends turned over toward one an-
other among the straw. The end wires clamp
the flanges b' with the side plates A, which 50
bulge out a little between their ends, so as to
make a more slighty broom. We propose to
press down so much of the edge of the plates
A as correspond with the flange part of the
shoulder-caps, so that when the broom is 55
made the outer surface of the edge of the caps
and plates will be smooth to the touch.

By our construction we make a cheap, effi-
cient, and durable broom-head, which will
tenaciously retain all the straw until the 60
broom has become useless from wear.

What we claim as new, and desire to protect
by Letters Patent, is—

1. In broom-heads, the two flat side plates
A, having the holes a, and the two curved 65
flanged end plates B, having the holes b, in
combination with the fasteners E, each formed
of a wire passed through said holes a b and
with the ends turned toward each other, sub-
stantially as shown and described. 70

2. A broom-head consisting of four plates
A A and B B, each having an integral projec-
tion C, adapted to be nailed to the handle, as
shown and described.

In testimony whereof we affix our signatures 75
in presence of two witnesses.

MOSES S. CLYDE.
WILLIAM WELSH.
